UNITED STATES PATENT OFFICE.

ANDREW NOBLE, OF NEWCASTLE-UPON-TYNE, ENGLAND, ASSIGNOR TO W. G. ARMSTRONG, MITCHELL & CO., (LIMITED,) OF SAME PLACE.

FUSE OR FIRING MECHANISM FOR PROJECTILES.

SPECIFICATION forming part of Letters Patent No. 372,699, dated November 8, 1887.

Application filed May 7, 1887. Serial No. 237,461. (No model.) Patented in England February 23, 1886, No. 2,654.

To all whom it may concern:

Be it known that I, ANDREW NOBLE, a subject of the Queen of Great Britain, late captain in the Royal Artillery, residing at Jesmondene House, Newcastle-upon-Tyne, England, manufacturing engineer, have invented certain new and useful Improvements in Fuses or Firing Mechanism for Projectiles, (for which a patent has been obtained in Great Britain, dated February 23, 1886, No. 2,654,) of which the following is a specification.

When shells with time-fuses are fired with light charges, there is some difficulty in making the fuse sufficiently sensitive to act with certainty when the ignition of the fuse composition depends on the inertia of a striker or part contained within the fuse.

In my improved fuse the ignition of the fuse composition is caused by an instrument which is forced forward by the pressure of the powder-gases upon it at the time of firing. In the center of the base of the projectile I provide a bush in which is a cylindrical cavity. In the cavity is a piston with a stem passing forward to the fore part of the projectile by an axial passage, around which shrapnel-bullets may be arranged. The stem terminates immediately in rear of the base of the fuse proper, which, as is usual, is screwed in at the apex of the projectile. This fuse may be an ordinary time-fuse, except as respects the ignition. This is effected by a needle in the axis of the fuse, pointed in front, and in rear provided with a head, which, when the fuse is in place, stands immediately in front of the stem of the piston previously mentioned. When on firing the piston moves forward, the stem strikes the head of the igniting-needle and throws its point against a fulminating priming immediately in front of it. The priming then fires the fuse composition, which burns for a longer or shorter time before lighting the bursting-charge, this being regulated in the usual way by the setting of the fuse before firing.

In order that my said invention may be more fully understood and readily carried into effect, I will proceed to describeth drawing hereunto annexed.

The drawing represents a longitudinal section of a shrapnel-shell.

A is a bush in the center of the base of the projectile, and B is a piston contained in a cylindrical cavity in the bush.

B' is a cup also inserted in the cylindrical cavity and abutting upon the piston. It serves to stop the powder-gases when the gun is fired, allowing, however, the piston to be driven forward by them.

C is a long stem attached to the piston.

D is an axial passage through the projectile, around which the shrapnel-bullets E are arranged.

F is an ordinary time-fuse screwed into the nose of the projectile. This time-fuse is of the ordinary construction, except that it is provided with a needle, G, and a priming, H. When the needle is driven against the priming H, the priming explodes and ignites the fuse. The needle and its guide are so arranged as to avoid all risk of the needle being driven forward by accidental violence, but so, nevertheless, that the needle advances with certainty on receiving the forward thrust of the piston and stem when these are projected forward by the pressure of the gases within the gun. For these purposes the needle is provided with a head, G', and the tubular guide I, through which the needle passes at its rear end, fits around the rear end of the needle, with the needle-head bearing against it, so that the point of the needle is held away from the priming, H, of fulminating material. The needle-guide, as shown, flares outwardly internally at rear, and the needle-head is made tapering, so as to project slightly into the rear end of the guide. A disk, G'', of thin brass is secured across the rear end of the body of the fuse, which is sufficient to insure that the needle shall not be driven forward against the priming by any ordinary blow from the piston-stem C. The guide I and disk G'' give way when the stem is driven forward on the projectile being fired from a gun. For further security a safety-wire, O, is passed through the stem C and through the bush A, and ordinarily holds back the stem and keeps it from striking against the disk G''.

K K are bags containing powder. The fuse

ignites the foremost of these, and the flash thereby produced passes to the other bags and through the tube D and ignites the bursting-charge contained in the tin receptacle L.

5 M is a disk of kampflicon interposed between the bullets and the wooden filling-block N, which keeps them in place.

Having now particularly described and ascertained the nature of my said invention and 10 in what manner the same is to be performed, I declare that what I claim is—

1. The combination of a projectile provided 15 with a cavity at the center of its base, a piston in such cavity, a forwardly-extending piston-stem, and a time-fuse at the fore end of the projectile, which is ignited by the blow of the stem when the stem is thrown violently forward, substantially as set forth.

2. The combination of a projectile provided

with a cavity at the center of its base, a piston 20 fitting within the cavity, a forwardly-extending piston-stem, a time-fuse at the nose of the projectile, a needle carried by the fuse in a line with and a short distance in front of the piston-stem, and provided with a head at its 25 rear end, the fuse-priming in advance of the needle, and a tubular guide of the fuse holding the needle back away from the priming, and which yields and allows the needle to be forced forward against the priming when the 30 piston-stem is thrown violently forward against the needle-head, substantially as set forth.

A. NOBLE.
